CLOSURE

Howard G. Mullett and Robert J. Book, Milwaukee, Wis., assignors to Bradley Washfountain Co., Milwaukee, Wis., a corporation of Wisconsin

Filed May 31, 1963, Ser. No. 284,624

8 Claims. (Cl. 220—25)

This invention relates to closures for the filling opening of a soap dispenser for a washfountain, or for other applications where it is necessary to close off an opening through a wall member; and it resides more particularly in the combination with a wall having an aperture therethrough of a rotatable cap disposed on one side of the wall and engageable therewith; a locking bar disposed on the other side of the wall; means to hold the bar and cap against relative rotation while allowing them to move toward and away from one another; ramp means cammingly engageable with the bar to move the bar away from the cap as the cap is rotated; bias means to urge the cap and bar together; and lock means to move the cap and bar toward one another.

Closures formed accordingly to this invention are particularly useful in connection with soap dispensers for group washfountains such as those commonly provided in schools and industrial plants. Such washfountains usually comprise a large basin and a central, 360° sprayhead for simultaneous use by a number of persons. A soap dispenser is often mounted above the sprayhead and usually comprises a reservoir for powdered or liquid soap and any suitable number of individual valves or other dispensing means. It is of course necessary to refill the reservoir at frequent intervals, and to this end the cover of the reservoir is usually provided with a filling opening with a suitable removable closure.

Presently available closures have not proven entirely satisfactory for soap dispensers, and they are usually either too difficult to operate or too easily tampered with. Since refilling of a soap dispenser is a frequent occurrence and is often done by unskilled persons, a dispenser closure must be easy to operate. On the other hand, pranks and vandalism are common in washrooms and dispensers closures are usually fully exposed, so that a closure which may be easily removed by unauthorized persons is wholly unsuitable. The closure must also provide an effective seal to prevent the wetting of powdered soap or the introduction of foreign matter which might ultimately clog the dispensing valve, contaminate the soap, or cause other damage.

It is the general object of this invention to provide an improved closure which provides an effective seal and which can be operated easily by authorized persons and which can easily be locked in place to prevent tampering. Although these attributes make the closure of this invention particularly suitable for soap dispensers, such a closure will be useful in a wide variety of applications.

The invention is not, therefore, intended to be limited to any particular use.

It is an object of this invention to provide a closure which may be manually operated and which may easily be locked in a closed position.

It is another object of this invention to provide a closure in which a visible cap is provided with a beveled edge to make it easy to grasp.

It is a further object of this invention to provide a closure in which a locking bar is mounted on a cap so that it is movable toward and away from the cap but is held against rotation relative to the cap so that the two rotate as a unit in a closing action and so that the bar may be moved toward the cap in a locking action.

It is still another object of this invention to provide a closure in which a ramp means which cammingly engages

2

a locking bar is provided with a reverse incline near one end to insure a positive holding and locking action.

It is a still further object of this invention to provide a closure in which stops are provided to limit the movement of a locking bar and cap beyond closed position and to prevent their rotation in the wrong direction.

It is still another object of this invention to provide a closure having an easily accessible tool operable lock means.

It is a still further object of this invention to provide a closure having a threaded lock means provided with a stop member to prevent it from being removed from the locking bar.

It is still another object of this invention to provide a closure having the foregoing advantages which is relatively simple and inexpensive to manufacture.

Further objects and advantages will appear from the description to follow. In the description, reference is made to the accompanying drawing, forming a part hereof, in which there is shown by illustration and not of limitation a particular embodiment of the invention.

In the drawing:

FIG. 1 is a fragmentary top plan view of the top wall of a soap dispenser showing a closure, formed according to this invention, in place,

FIG. 2 is a bottom plan view of the closure of FIG. 1,

FIG. 3 is a bottom plan view of the closure of FIG. 1 that is similar to FIG. 2, but shows the cap and locking bar in a closed position,

FIG. 4 is a view in cross section taken along the plane 4—4 shown in FIG. 1,

FIG. 5 is a fragmentary view in cross section taken along the plane 5—5 shown in FIG. 3, and

FIG. 6 is a fragmentary view in cross section taken along the plane 6—6 shown in FIG. 2.

In the drawing, the reference numeral 1 refers to the plastic top wall or cover of a soap dispenser or similar receptacle (not shown). Again, it should be remembered that the closure of this invention is useful in a wide variety of applications. For this reason, and since the structure and operation of the closure can be understood without reference to any particular receptacle or other structure, the soap dispenser has not been shown or described herein. For one illustration of a soap dispenser in which a closure formed according to this invention may be used, reference may be had to U.S. Patent No. 2,376,551 issued May 22, 1945 to H. G. Mullett et al.

The wall 1 has a substantially circular aperture therethrough which is provided with a pair of substantially diametrically opposite, generally rectangular cutout portions or recesses 3 which serve as lateral extensions of the aperture 2. The underside of the wall 1, that surface seen in FIGS. 2 and 3, is provided with an integral upstanding rim 4, which extends about substantially the entire circumference of the aperture 2 except for those portions occupied by the recesses 3.

As can be seen most clearly in FIGS. 2, 3 and 5, the underside of the wall 1 is also provided with a pair of integral ramp means 5 which extend outwardly from the rim 4. The ramp means 5 begin near opposite sides of the recesses 3, with each ramp 5 extending from a point near its associated recess 3 and thence about the circumference of the aperture 2 to terminate approximately on a line perpendicular to a line drawn between the recesses 3. Each ramp 5 begins at the level of the rim 4 and inclines outwardly from the wall 1 to an apex 6 intermediate its ends. From the apex 6, each ramp 5 is provided with a reverse incline toward the wall 1 which continues until the ramp 5 terminates at an upstanding stop projection 7. The two ramps 5 are substantially diametrically opposite; that is, they have their corresponding points substantially on opposite sides of the center of

the aperture 2. A second pair of stop projections 8 are provided at the remaining sides of the recesses 3, those sides opposite to the sides near which the ramps 5 begin, and serve to prevent rotation of a cap and lock bar in the wrong direction as will be described.

As can be seen in FIG. 4, the upper surface of the wall 1 is also provided with an upstanding rim 9. The rim 9 extends about the entire aperture 2, being notched at the recesses 3. The rims 4 and 9 serve to strengthen the wall 1. In those cases where a closure formed according to the invention is to be used with a curved wall member, rims such as the rims 4 and 9, are also useful in providing flat operating and sealing surfaces about the aperture 2. It can be seen from FIG. 4, that the aperture 2 tapers outwardly slightly from the bottom of the wall 1, which is actually the top of the rim 4, to the top of the rim 9.

A generally circular, plate-like plastic cap 10 engages the upper surface of the wall 1, the surface seen in FIG. 1, with the outer edge of its inner side in sealing contact with the rim 9, the cap 10 thus serving to close off the aperture 2. As can be seen from FIG. 4, the edge of the cap 10 is beveled or tapered inwardly from top to bottom for ease in handling as will be described.

The cap 10 is provided on its bottom or inner side with a pair of integral downwardly extending, substantially diametrically opposite projections 11 each provided with a downwardly opening, flat bottomed notch 12. At about the center of the cap 10, intermediate the projections 11, there is a downwardly extending integral block 13 having a smooth, vertical stepped bore 14 extending therethrough. A lock means in the form of a threaded screw 15, having an operating head 16, is slidably and rotatably received through the bore 14 with the head 16 being received in the relatively larger upper portion of the bore 14, as can be seen in FIG. 4.

A compression spring 17 is seated in the intermediate portion of the bore 14 and acts between the floor of the intermediate portion of the bore 14 and the head 16 to urge the screw 15 in an upward direction as seen in FIG. 4.

A generally rectangular metal locking bar 18 is threadedly mounted on the downwardly projecting end of the screw 15, the bar 18 thus being mounted on or connected to the cap 10. The lower end of the screw 15 is provided with a groove which receives a lock washer 19 which prevents the screw 15 from being removed from the bar 18.

As can be seen clearly in FIGS. 2, 3 and 6, the bar 18 is provided with narrowed end portions 20 which are received in the notches 12 of the projections 11. Because the ends 20 are disposed in the notches 12, the bar 18 is held against rotational movement relative to the cap 10 but is allowed to move toward and away from the cap 10. The projections 11 and the block 13 serve to limit movement of the bar 18 toward the cap 10.

The bar 18 is normally in the position shown in FIG. 4; that is, it is held against the projections 11 and block 13 by the spring 17. The screw 15 and bar 18 are adjusted so that in this normal position there is, as can be seen in FIG. 4, a clearance between the head 16 and its seat in the bore 14. This clearance allows the bar 18 to be moved downwardly in a closing action as will be described. The projections 11 and block 13 are of sufficient height so that when the bar 18 is in the normal position shown in FIG. 4 the distance between the bar 18 and the cap 10 is slightly greater than the thickness of the wall 1, which at the aperture 2 is the distance between the tops of the rims 4 and 9.

As can be seen clearly in FIG. 2, the bar 18 is longer than the diameter of the aperture 2, but is shorter than the distance between the remote ends of the recesses 3 so that it can pass through the aperture 2 only when the narrowed ends 20 are in alignment with the recesses 3.

The operation of the closure can be understood with particular reference to FIGS. 2, 3 and 5. In a closing action, the cap 10 and bar 18 are placed in the position

shown in FIG. 2 wherein the ends 20 of the bar 18 are in alignment with the recesses 3. The bar 18 may then be inserted through the aperture 2 and the upper surface of the bar 18 will then be slightly below the top of the rim 4. The cap 10 is then rotated in a counterclockwise direction as seen in FIGS. 2 and 3, with the engagement between the ends 20 and notches 12 causing the bar 18 to be rotated with the cap 10 as a unit. The stops 8 prevent the cap 10 and bar 18 from being rotated in a clockwise direction as seen in FIGS. 2 and 3.

As the cap 10 is rotated, the ends 20 of the bar 18 come into contact with the ends of the ramps 5, and as rotation continues they ride up the ramps 5 in a camming action, thus moving the bar 18 against the spring 17 and away from the cap 10. Rotation can continue only until the ends 20 come into contact with the stops 7. By the time this occurs, the ends 20 have passed the apices of the ramps 5 and are in the position shown in FIG. 5. From FIG. 5, it can be seen that at the conclusion of a closing action an edge, the upper left hand edge as seen in FIG. 5, of each end 20 bears against the reverse incline below the apex 6, this engagement serving as a positive stop to retard return movement of the bar 18.

When the closure is in closed position, the position shown in FIGS. 3 and 5, the spring 17 urges the cap 10 and bar 18 together against the wall 1, and the engagement of the ends 20 on the reverse inclines of the ramps 5 serves as a positive stop to hold the closure against opening. When it is desired to remove the closure, the cap 10 is rotated in a clockwise direction as seen in FIG. 3 with sufficient force so that the camming action between the ends 20 and reverse inclines causes the bar 18 to be moved against the spring 17 and away from the cap 10 so that the ends 20 can ride over the apices 6. Continued rotation then brings the closure to the position of FIG. 2 where the ends 20 are in alignment with the recesses 3 and the cap 10 and bar 18 may then be lifted from the aperture 2.

As can be seen from the drawing, the cap 10 is relatively thin and is set quite close to the wall 1, being raised only by the height of the rim 9. This substantially flush mounting would ordinarily make the cap 10 quite difficult to grasp for opening and closing. The inwardly beveled edges of the cap 10, however, make it quite easy to grasp the cap 10 and rotate it for closing and opening. Thus, the cap 10 can have a substantially flush appearance, which also reduces the possibility of catching dirt or foreign matter, while still being easy to handle.

Ordinarily, the force of the spring 17 will be enough to hold the cap 10 in place. When, because of the possibility of vandalism or otherwise, it is desired to lock the cap 10 in place, however, the screw 15 may be used to draw the bar 18 tightly against the underside of the wall 1, the screw 15 thus serving as a screw lock means. As can be seen in FIG. 1, the head 16 of the screw 15 is provided with a hexagonal socket 21. The head 16 is substantially flush with or below the top of the cap 10, so that, although rotation of the screw 15 can be accomplished readily by inserting a suitable tool into the socket 21, manual rotation by unauthorized persons is practically impossible. It will be readily appreciated that the force exerted by the screw 15 in combination with the engagement between the ends 20 and the reverse inclines of the ramps 5 will make it virtually impossible to remove the cap 10 manually once the screw 15 has been tightened. The engagement of the ends 20 and the notches 12 prevents rotation of the bar 18 while the screw 15 is being tightened. For unlocking, it is necessary only to loosen the screw 15 and the closure can then be removed in the manner described above. The lock washer 19 prevents accidentally removing the screw 15 from the bar 18 during an unlocking action.

One of the important features of the invention is the provision of the projections 11 and notches 12 which serve to allow movement of the bar 18 toward and away from the cap 10 to allow a camming action by the ramps 5.

The bar 18 is, however, prevented from rotation with respect to the cap 10 so that the two rotate together as a unit. The notches 12 also prevent rotation of the bar 18 during tightening of the screw 15.

Although a preferred embodiment of the invention has been shown and described herein, a number of variations might be made without departure from the invention. For example, although a ramp with a reverse incline is particularly suitable in that it provides a positive stop or lock, a straight ramp may be used and tightening of the screw will still make the closure extremely difficult to open manually. The invention is not, therefore, intended to be limited except insofar as such limitations appear in the following claims.

We claim:

1. In a closure, the combination with a wall having an aperture therethrough of a rotatable cap disposed on one side of the wall and engageable therewith; a locking bar connected to the cap and disposed on the opposite side of the wall; means to hold the bar and cap against relative rotation and to allow the bar and cap to move toward and away from one another; bias means to urge the bar and cap together; ramp means interposed between opposite side of the wall and the bar and adapted to cause a camming engagement therebetween which moves the bar away from the cap as the cap is rotated; and lock means separate from the ramp means to move the bar and cap toward one another.

2. In a closure, the combination with a wall having an aperture therethrough of a rotatable cap disposed on one side of the wall and having an inner side engageable therewith to close off the aperture; a locking bar connected to the cap and disposed on the opposite side of the wall; projecting means on said cap adapted to be inserted through the aperture, said bar being received in said projecting means to be held against rotation relative to the cap while being capable of movement toward and away from the cap; bias means to urge the bar toward the cap; ramp means on and extending outwardly from said opposite side of the wall, said ramp means being inclined outwardly from said opposite side of the wall and being cammingly engageable with the bar to move the bar away from the cap as the cap is rotated; and lock means separate from the ramp means to move the bar toward the cap.

3. In a closure, the combination with a wall having a substantially circular aperture therethrough with a pair of substantially diametrically opposite recesses, of a rotatable cap disposed on one side of the wall and having an inner side engageable therewith to close off the aperture and recesses; an elongated locking bar disposed on the opposite side of the wall that is longer than the diameter of the aperture and shorter than the distance between the remote ends of the recesses; a screw lock means having an operating head at the outer side of the cap and an inner end threadedly engaged with the bar, whereby operation of the screw will cause the bar to be moved toward the cap; a pair of oppositely disposed projecting means on the inner side of the cap, each having an outwardly opening notch receiving an end portion of the bar, whereby the bar is held against rotation relative to the cap while being capable of movement toward and away from the cap; bias means acting between the cap and the operating head of the screw lock means to urge the bar toward the cap; and a pair of ramp means on said opposite side of the wall beginning near opposite sides of the recesses, each ramp means being inclined outwardly

from said opposite side of the wall to an apex and being provided with a reverse incline leading from the apex and having an upwardly extending stop projection at the end of the reverse incline, said ramps being cammingly engageable with end portions of the bar.

5 4. A closure according to claim 3 wherein a block extending toward the bar is mounted on the inner surface of the cap, said block having a smooth, stepped bore therethrough through which the screw lock means is slidably and rotatably received, said bore including a relatively smallest portion nearest the bar, an intermediate portion, and a relatively largest portion at the outer side of the cap within which the operating head of the screw lock means is received, and wherein the bias means is a compression spring disposed about the shaft of the screw lock means and received in the intermediate portion of the bore.

10 5. A closure according to claim 3 wherein there is a second pair of stop projections on said opposite side of the wall, one located immediately adjacent the side of each recess opposite the side near which an associated ramp means begins.

15 6. A closure according to claim 3 wherein the cap is plate-like with its edge tapered inwardly from its outer side to its inner side.

20 7. In a closure for an aperture through a wall, the combination comprising: a rotatable cap having inner and outer sides and adapted to close off the aperture; an elongated locking bar; a screw lock means extending through the cap with an operating head at the other side of the cap and an inner end threadedly engaged with the bar, whereby operation of the screw will cause the bar to be moved toward the cap; a pair of oppositely disposed projecting means on the inner side of the cap that are adapted to pass through the aperture, each having a notch opening axially away from the inner side of the cap and receiving an end portion of the bar, whereby the bar is held against rotation relative to the cap while being capable of movement toward and away from the cap; and bias means acting between the cap and the operating head of the screw lock means to urge the bar toward the cap.

25 8. In a closure, the combination with a wall having an aperture therethrough of a rotatable cap disposed on one side of the wall and having an inner side engageable therewith to close off the aperture; a locking bar connected to the cap and disposed on the opposite side of the wall; projecting means on said cap having an outwardly opening notch, said bar being received in said notch to be held against rotation relative to the cap while being capable of movement toward and away from the cap; bias means to urge the bar toward the cap; ramp means on said opposite side of the wall, said ramp means including away from said opposite side of the wall to an apex and thence having a reverse incline toward said opposite side, there being a projecting stop means at the end of the reverse incline, said ramp means being cammingly engageable with the bar to move the bar away from the cap as the cap is rotated; and lock means to move the bar toward the cap.

30 9. In a closure, the combination with a wall having an aperture therethrough of a rotatable cap disposed on one side of the wall and having an inner side engageable therewith to close off the aperture; a locking bar connected to the cap and disposed on the opposite side of the wall; projecting means on said cap having an outwardly opening notch, said bar being received in said notch to be held against rotation relative to the cap while being capable of movement toward and away from the cap; bias means to urge the bar toward the cap; ramp means on said opposite side of the wall, said ramp means including away from said opposite side of the wall to an apex and thence having a reverse incline toward said opposite side, there being a projecting stop means at the end of the reverse incline, said ramp means being cammingly engageable with the bar to move the bar away from the cap as the cap is rotated; and lock means to move the bar toward the cap.

35 10. In a closure, the combination with a wall having an aperture therethrough of a rotatable cap disposed on one side of the wall and having an inner side engageable therewith to close off the aperture; a locking bar connected to the cap and disposed on the opposite side of the wall; projecting means on said cap having an outwardly opening notch, said bar being received in said notch to be held against rotation relative to the cap while being capable of movement toward and away from the cap; bias means to urge the bar toward the cap; ramp means on said opposite side of the wall, said ramp means including away from said opposite side of the wall to an apex and thence having a reverse incline toward said opposite side, there being a projecting stop means at the end of the reverse incline, said ramp means being cammingly engageable with the bar to move the bar away from the cap as the cap is rotated; and lock means to move the bar toward the cap.

40 11. In a closure, the combination with a wall having an aperture therethrough of a rotatable cap disposed on one side of the wall and having an inner side engageable therewith to close off the aperture; a locking bar connected to the cap and disposed on the opposite side of the wall; projecting means on said cap having an outwardly opening notch, said bar being received in said notch to be held against rotation relative to the cap while being capable of movement toward and away from the cap; bias means to urge the bar toward the cap; ramp means on said opposite side of the wall, said ramp means including away from said opposite side of the wall to an apex and thence having a reverse incline toward said opposite side, there being a projecting stop means at the end of the reverse incline, said ramp means being cammingly engageable with the bar to move the bar away from the cap as the cap is rotated; and lock means to move the bar toward the cap.

45 12. In a closure, the combination with a wall having an aperture therethrough of a rotatable cap disposed on one side of the wall and having an inner side engageable therewith to close off the aperture; a locking bar connected to the cap and disposed on the opposite side of the wall; projecting means on said cap having an outwardly opening notch, said bar being received in said notch to be held against rotation relative to the cap while being capable of movement toward and away from the cap; bias means to urge the bar toward the cap; ramp means on said opposite side of the wall, said ramp means including away from said opposite side of the wall to an apex and thence having a reverse incline toward said opposite side, there being a projecting stop means at the end of the reverse incline, said ramp means being cammingly engageable with the bar to move the bar away from the cap as the cap is rotated; and lock means to move the bar toward the cap.

50 13. In a closure, the combination with a wall having an aperture therethrough of a rotatable cap disposed on one side of the wall and having an inner side engageable therewith to close off the aperture; a locking bar connected to the cap and disposed on the opposite side of the wall; projecting means on said cap having an outwardly opening notch, said bar being received in said notch to be held against rotation relative to the cap while being capable of movement toward and away from the cap; bias means to urge the bar toward the cap; ramp means on said opposite side of the wall, said ramp means including away from said opposite side of the wall to an apex and thence having a reverse incline toward said opposite side, there being a projecting stop means at the end of the reverse incline, said ramp means being cammingly engageable with the bar to move the bar away from the cap as the cap is rotated; and lock means to move the bar toward the cap.

55 14. In a closure, the combination with a wall having an aperture therethrough of a rotatable cap disposed on one side of the wall and having an inner side engageable therewith to close off the aperture; a locking bar connected to the cap and disposed on the opposite side of the wall; projecting means on said cap having an outwardly opening notch, said bar being received in said notch to be held against rotation relative to the cap while being capable of movement toward and away from the cap; bias means to urge the bar toward the cap; ramp means on said opposite side of the wall, said ramp means including away from said opposite side of the wall to an apex and thence having a reverse incline toward said opposite side, there being a projecting stop means at the end of the reverse incline, said ramp means being cammingly engageable with the bar to move the bar away from the cap as the cap is rotated; and lock means to move the bar toward the cap.

60 15. In a closure, the combination with a wall having an aperture therethrough of a rotatable cap disposed on one side of the wall and having an inner side engageable therewith to close off the aperture; a locking bar connected to the cap and disposed on the opposite side of the wall; projecting means on said cap having an outwardly opening notch, said bar being received in said notch to be held against rotation relative to the cap while being capable of movement toward and away from the cap; bias means to urge the bar toward the cap; ramp means on said opposite side of the wall, said ramp means including away from said opposite side of the wall to an apex and thence having a reverse incline toward said opposite side, there being a projecting stop means at the end of the reverse incline, said ramp means being cammingly engageable with the bar to move the bar away from the cap as the cap is rotated; and lock means to move the bar toward the cap.
